BALLAST APPARATUS

Roger E. Hume, Danville, Ill., assignor to General Electric Company, a corporation of New York

Filed Aug. 17, 1959, Ser. No. 834,317

6 Claims. (Cl. 315—138)

This invention relates to ballast apparatus for starting and operating gaseous discharge lamps such as fluorescent lamps. It is concerned with ballast apparatus especially advantageous for use with the so called instant start type of lamp which requires an instantaneously high voltage sufficient to initiate the gaseous discharge in the lamp without the necessity of heating the elements thereof. Once the discharge has been initiated in the lamp, it is then required of the ballast apparatus that current flow be limited for the reasons well-known and inherent to gaseous discharge lamps.

One popular form of ballast apparatus used with fluorescent lamps, and particularly with instant start lamps, is arranged for sequentially igniting and controlling the current to a pair of lamps connected in series circuit relation with each other. Such ballasts and circuits are described, for example, in United States Patent 2,358,810—Karash and in United States Patent 2,558,293—Feinberg. In such apparatus, an auxiliary high reactance element provides voltage for igniting one of the lamps and the resultant current through this ignited lamp functions in conjunction with other reactance elements in the circuit to ignite the other serially connected lamp. After both lamps are started, they are then operated by the apparatus in series circuit relation with the auxiliary high reactance element being substantially bypassed by the lamp current. For economy and simplicity, all of the desired inductive reactance elements are now generally provided by separate secondary windings on a unitary magnetic core structure forming a single high-reactance transformer in which the starting reactance or winding is arranged on one side of the primary winding and the ballasting reactance or winding is on the other side of the primary winding. This form of ballast apparatus is commonly known as a "series sequence" ballast. Besides this common arrangement, it has also been suggested, as for example in United States Patent 2,683,243—Feinberg, that a portion of the ballasting winding may be wound over the primary winding in additive voltage relation thereto for increasing the voltage applied to the lamps during their operation.

Difficulty has been experienced, however, in economically adapting the series sequence ballast design to "high-voltages," for example, to discharge devices operating from a 277 volt supply source. As is well-known, normal residential and commercial distribution voltage is in the range from 110 to 240 volts; industrial voltages are generally distributed at 220 to 480 volts. In a three phase 480 volt system, the line to neutral of the system is at approximately 277 volts, and there is presently a growing demand for lighting circuits to operate from 277 volt circuits.

Due to the limited demand for lamp systems operating on such high-voltages, it is not economical to design a separate ballast core for the high-voltages ballast. Present design philosophy for series sequence ballasts for starting and operating instant start lamps is that the high volume 120 volt 60 cycle core design is the basic design. From an economical standpoint, this basic design usually

has a core developed for optimum performance at the lowest possible cost at the high volume voltage. Because of low volume, ballasts for other voltages and frequencies of this type are of secondary nature in as far as expended design effort is concerned; it is, therefore, desirable that the 277 volt input ballasts be designed on the 120 volt ballast core. However, for ballast designs using the 120 volt core, but in the 265 and 277 volt range, difficulty is encountered in proper operation of the lamps. For example, if a 277 volt ballast were being designed on the 120 volt core punching, the primary winding could easily be changed and put in the same physical space as the 120 volt primary winding; but, a higher voltage would appear across the starting winding and would cause higher, abnormal current in the starting winding. The increased current would make the starting winding exceed coil temperature requirements. Ballast turns could not be added to the starting winding to increase the impedance due to the space limitation. In the ballasting circuit under normal conditions, the added voltage would cause poor lamp current wave form, considerable unbalance between lamps, high capacitor voltage and a hotter unit. If the higher voltage is compensated for by removing turns from the ballasting winding, this produces a greater problem of low frequency variation in light output or instability.

Certain improved ballast apparatus described and claimed in co-pending application Serial No. 829,148, filed on July 23, 1959 by Daniel Lovinger, as a continuation-in-part of his earlier application Serial No. 789,701, now abandoned, and assigned to the same assignee as the present invention, overcomes the aforementioned difficulties. The instant invention is an improvement over the invention described in the aforesaid Lovinger applications as well as over the apparatus disclosed in the aforementioned Karash and Feinberg patents; and it has as its primary object the provision of an improved ballast apparatus for initiating the discharge of a pair of instant start lamps and for thereafter operating the same, which apparatus is economically capable of being adapted to operate on high-voltage sources.

Another object of the invention is to provide an improved ballast apparatus which is arranged for energization from a high-voltage source, but may use the same magnetic core as ballast apparatus adapted for energization from a lower voltage source.

A further object is to provide an improved ballast apparatus for use with a high voltage source, which operates at high efficiency to start and operate a pair of instant start lamps.

As mentioned above, the series sequence ballasts commonly used today have all of their windings positioned on a single magnetic core. In particular, one popular ballast comprises an autotransformer having a primary, a loosely coupled first or auxiliary starting secondary having one side connected to one side of the primary and in additive voltage relationship thereto, and a loosely connected second or operating secondary more closely coupled to the primary than the first secondary and having one side connected to the other side of the first secondary and in opposing or bucking voltage relationship to the first secondary. One of the lamps is connected in series with a capacitive reactor across the primary and the first secondary, and the second of the lamps is connected across the first and second secondaries in series. In the apparatus disclosed in the aforesaid Lovinger application Serial No. 829,148, the transformer is modified for high-voltages in excess of the normal commercial and residential voltage by the addition of a third secondary coil closely coupled to the primary coil and bucking the combined terminal voltage of the primary coil and second or operating secondary. According to the present invention,

the third or bucking secondary is so arranged and connected that it opposes the voltages of the primary and the operating secondary during the operation of the lamps, but does not oppose the voltage of the operating secondary in the starting circuits for the lamps. Thereby, an improved ballast is provided giving good lamp balance and operating at high efficiency.

The subject matter which I regard as my invention is particularly pointed out and distinctly claimed in the concluding portion of this specification. My invention, however, both as to organization and method of operation, together with further objects and advantages thereof, may be best understood by reference to the following description taken in conjunction with the accompanying drawing, in which:

Fig. 1 is a schematic diagram illustrating a ballast apparatus embodying my invention connected to start and operate two gaseous discharge lamps; and,

Fig. 2 is a plan view of the ballast apparatus included in arrangement of Fig. 1.

Referring to Figs. 1 and 2, the illustrated embodiment of my invention employs a magnetic core 1, which includes a center winding leg 2 and an enclosing yoke 3. Several independently formed windings are wound on the center leg 2, including a primary winding P, a first or starting secondary winding S₁, a second or operating secondary winding S₂, and a third or voltage compensating secondary winding S₃. The secondary windings are in inductive relationship to the primary winding, all being wound on the common magnetic winding leg 2. The first secondary S₁ and the second secondary S₂ are both loosely coupled to the primary P, but the third secondary S₃ is closely coupled to the primary P.

In the illustrated embodiment the third secondary S₃ is wound directly over the primary P to provide the desired close coupling. With this arrangement there is, of course, substantially no leakage reactance between the primary and winding S₃. It will be understood, however, that in alternate embodiments of the invention the secondary S₃ could be positioned immediately beside the primary P on the winding leg 2 instead of being wound over the primary. With this alternate arrangement the winding S₃ would be relatively short in length and would be quite closely coupled to the primary, with relatively little leakage flux therebetween. As in the illustrated embodiment, the winding S₃ would be much more closely coupled to the primary than either of the windings S₁ and S₂, whose arrangement will now be described.

As shown, the first or starting secondary S₁ is positioned adjacent one end of the winding leg 2 spaced from the primary P and with a flux leakage path or shunt 4 formed between it and the primary. The leakage path 4 is formed by oppositely disposed projections on the yoke 3 which project inwardly toward the winding leg 2, with an air gap between them and the winding leg at their inner ends. With this arrangement, the starting secondary S₁ is loosely coupled to the primary P, having a rather high leakage reactance. The other or operating secondary S₂ is positioned on the opposite end of the winding leg with a flux leakage path or shunt 5 formed between it and the primary P. With this arrangement, the winding S₂ is also a high reactance winding, loosely coupled to the primary P, but in the illustrated embodiment its arrangement is such that it is more closely coupled to the primary than the starting secondary S₁. It will be understood, incidentally that the present invention is not limited to any particular arrangement for providing flux leakage paths or shunts between the primary P and the secondaries S₁ and S₂ since depending upon the design of the transformer, either air leakage paths or projections on the core may be used to provide the desired flux leakage arrangements. Whatever arrangement is used, however, the starting secondary S₁ will be of a higher reactance than the operating secondary S₂.

The windings of the transformer 1 are connected, in the illustrated embodiment of my invention, in the circuit of Fig. 1, and the relative directions of the open circuit or generated voltages therein are indicated by the arrows next to the respective windings.

In the circuit of Fig. 1, the starting secondary winding S₁ is connected in autotransformer relationship to the primary P at juncture 6, and is arranged so that its open circuit voltage is additive to that of the primary. The third secondary winding S₃ is connected in autotransformer relation to the other end of winding S₁ at connection point 7, but it is arranged in an opposite open-circuit electrical direction to provide open-circuit bucking or opposing voltage to the first secondary winding S₁ and primary winding P. The primary P and the secondaries S₁ and S₃ are all connected in series circuit relation in a loop for starting the lamp L₁, as will be explained hereinafter. The operating secondary winding S₂ is also connected to the end of the secondary S₁ remote from the primary P, and it is arranged in an opposite or bucking open-circuit electrical sense to the starting secondary winding S₁ in a second series loop including lamp L₂ but excluding the lamp L₁. In this second loop the lamp L₂ is serially connected with both secondaries S₁ and S₂. Also, as will be further described below, secondary S₂ and secondary S₃ are both included in the normal series operating loop including both lamps L₁ and L₂, with S₃ providing a generally opposing or bucking voltage to S₂ in the operating loop.

30 The primary winding P is provided with leads 8 and 9 for connection across a source of alternating current voltage, and leads 10 and 11 extend from the ballasting apparatus for connection to a first discharge lamp L₁. The lead 10 is connected to one side of the primary P as by input lead 8, and the lead 11 is connected to the end of secondary S₃ remote from connection point 7. As shown, a capacitive reactor 12 is serially connected in the lead 11 between winding S₃ and lamp L₁. When lamp L₁ is placed across the leads 10 and 11, it is thereby connected in a series starting loop comprising the primary winding P, the starting secondary winding S₁, the third secondary winding S₃ and the capacitive reactor 12. Winding S₃ provides a bucking voltage to the primary P and secondary S₁ in this loop, but the combined open-circuit voltage of the primary P and the starting secondary S₁ is much greater than that of secondary S₃ so that sufficient voltage is supplied to lamp L₁ to start lamp L₁.

Another set of leads 13 and 14 extend from the ballasting apparatus for connection to the second lamp L₂. The lead 13 is connected to the other side of the primary from lead 10, i.e., to input lead 9, and the lead 14 is connected to the end of the operating secondary S₂ remote from point 7. The leads 13 and 14 thus connect the lamp L₂ in a series loop comprising it and the secondaries S₁ and S₂. This loop, as will now be explained, is effective to ignite the lamp L₂ once the lamp L₁ has been ignited by its starting loop. Specifically after the lamp L₁ has started, current flows in the starting loop including lamp L₁ and since the inductive reactance of the loosely coupled starting secondary S₁ is great compared to the capacitive reactance of the reactor 12, the current in the loop is lagging. The lagging current flow caused by the ignition of the first lamp L₁ gives rise to a reactive voltage in the starting secondary S₁ whose phase is in effect reversed relative to the phase of voltage in the primary P and hence is generally additive relative to the voltage induced in the operating secondary S₂. This voltage is of such magnitude that the combined voltage appearing across lamp L₂ from secondary windings S₁ and S₂ is sufficient to ignite the lamp L₂. Lamps L₁ and L₂ are thereby started sequentially. It will be especially noted that winding S₃ does not supply any bucking voltage in the loop for starting lamp L₂.

With both lamps operating, the operating loop consists of a series circuit connected across the primary P. Start-

ing at lead 9, this circuit comprises lead 13, the lamp L_2 , lead 14, the operating secondary winding S_2 , the third secondary winding S_3 , the capacitive reactor 12, lead 11, the first lamp L_1 , and lead 10 back to the other input lead 8. Because of the very high reactance of the starting secondary S_1 , it carries very little operating current, and therefore, is not considered as part of the operating circuit. It will be seen that the voltages of the primary P and the operating secondary S_2 are additive in the operating loop, but that the voltage of S_3 is in opposing or buckling relation in the loop.

As heretofore explained, where the source voltage is higher than the normal 120 volt commercial and residential voltage, for example, as where the above-mentioned 277 volt high voltage is employed, the voltage in the operating circuit, without the addition of the bucking voltage of the third secondary S_3 , would exceed the normal operating voltage needed for the lamps, thereby distorting the lamp balance. The provision of the bucking voltage produced by third secondary winding S_3 , permits normal operation of the lamp circuit; it is not necessary to sacrifice operating secondary reactance by the removal of turns from the operating or ballasting secondary S_2 . The voltage of the secondary S_3 reduces the total voltage in the operating circuit to the desired amount without reducing the inductive ballasting reactance and thereby provides for efficient lamp operation.

In a typical embodiment of my ballast apparatus, intended for use with a voltage source of 277 volts to energize two 96T12 instant start lamps, the windings are arranged so that the open-circuit induced voltage in the starting secondary S_1 is approximately 625 volts, the open-circuit induced voltage in the operating winding S_2 is approximately 350 volts, and the open-circuit induced voltage in the third or bucking winding S_3 is approximately 159 volts. During the steady state operation of the ballast, the lamps are in good balance with a current of approximately 0.405 ampere flowing in lamp L_1 and approximately 0.395 ampere in lamp L_2 . The ballast has the very considerable advantage that it uses the same core as is normally used for the higher volume 120 volt ballasts, whereby it may be inexpensively produced without design, tooling and other expense necessary for a special core. Further, of any ballasts known to me for use with a 277 volt supply to energize two 96T12 instant start lamps, this ballast consumes the least volt-amperes. Thus, from an operating or efficiency standpoint, as well as a manufacturing viewpoint, the ballast is quite desirable.

In accordance with the Patent Statutes, I have described what at present is considered to be the preferred embodiment of my invention. However, it will be obvious to those skilled in the art that various changes and modifications may be made in the disclosed structure without departing from my invention, and it is, therefore, aimed in the appended claims to cover all such changes and modifications as fall within the true spirit and scope of my invention.

What I claim as new and desire to secure by Letters Patent of the United States is:

1. Apparatus for igniting and operating a pair of gaseous discharge lamps from a source of high voltage supply comprising a magnetic core having wound thereon a primary winding, a first high reactance secondary winding loosely coupled to said primary winding, a second high reactance secondary winding loosely coupled to said primary winding, and a third secondary winding more closely coupled to said primary winding than either of said first or second secondary windings; means connecting said first secondary winding to said primary winding in autotransformer relationship with their open-circuit voltages in aiding relation, means connecting said third secondary winding in autotransformer relationship with both said first secondary winding and said second secondary winding in open-circuit opposing voltage re-

lationship to both said first and second secondary windings, leads for connecting a first discharge lamp in a starting loop including said third secondary winding, said first secondary winding and said primary winding all serially connected, and for connecting the second lamp in a starting loop including said first secondary winding and said second secondary winding, and for connecting both lamps in a series operating loop including said primary winding, said third secondary winding and said second secondary winding, all serially connected, said third secondary winding being in opposing voltage relation to said primary winding and said second secondary winding thereby to reduce the operating voltage applied to said lamps without substantially affecting the inductive ballasting reactance in said circuit and said first secondary winding having sufficient reactance so that said first secondary winding is substantially isolated from said operating loop when said lamps are ignited.

2. Apparatus for sequentially igniting and operating a pair of gaseous discharge lamps in a series operating circuit from a source of high voltage supply comprising a magnetic core having wound thereon a primary winding, a first high reactance secondary winding, said first secondary winding having sufficient reactance to be substantially isolated from said series operating circuit a second high reactance secondary winding, and a third secondary winding placed on said primary winding and closely coupled thereto, flux leakage paths between said primary winding and each of said first and second secondary windings, said first secondary winding having one end connected to said primary winding in autotransformer relationship with their open-circuit voltages in aiding relation, said third secondary winding having one end connected to both said first secondary winding and said second secondary winding and arranged in open-circuit opposing voltage relationship to both said first secondary winding and said second secondary winding, a capacitive reactor, leads for connecting a first discharge lamp in a starting loop including said capacitive reactor, said third secondary winding, said first secondary winding and said primary winding all serially connected, for connecting the second lamp in a starting loop including said first secondary winding and said second secondary winding, and for connecting both lamps in a series operating loop across the capacitive reactor, the primary winding, all serially connected, said third secondary winding being in opposing voltage relation to said primary winding and said second secondary winding thereby to reduce the operating voltage applied to said lamps without substantially affecting the inductive ballasting reactance in said circuit.

3. Apparatus for igniting and operating a pair of gaseous discharge lamps from a source of high voltage supply comprising a magnetic core having wound thereon a primary winding, a first high reactance secondary winding, a second high reactance secondary winding, and a third secondary winding closely coupled to said primary winding, flux leakage paths between said primary winding and each of said first and second secondary windings, said first secondary winding having one end connected to said primary winding in autotransformer relationship and having an open-circuit voltage in aiding relation therewith, said third secondary winding having one end connected to both said first secondary winding and said second secondary winding and arranged in open-circuit opposing voltage relationship to both said first secondary winding and said second secondary winding, leads for connecting a first discharge lamp in a starting loop including said third secondary winding, said first secondary winding and said primary winding all serially connected, and for connecting the second lamp in a starting loop including said first secondary winding and said second secondary winding, said leads connecting both lamps in a series operating loop including said primary winding, said third secondary winding, and said second secondary

winding, all serially connected, said third secondary winding being in opposing voltage relation to said primary winding and said second secondary winding and said first secondary winding having sufficient reactance so that said first winding is substantially isolated from said series operating loop.

4. Ballast apparatus for sequentially starting and operating a pair of gaseous discharge lamps in a series operating circuit from an alternating current source, comprising a multiple winding transformer having a primary winding for connection to said alternating current source, a ballasting secondary winding loosely coupled to said primary winding, a starting secondary winding loosely coupled to said primary winding and having sufficient reactance to be substantially isolated from said series operating circuit, and a third secondary winding closely coupled to said primary winding, means for connecting a part of said transformer including at least said starting secondary winding for applying igniting voltage to one of said lamps, means for connecting a part of said transformer including said starting and ballasting windings and excluding said third winding for applying igniting voltage to the other of said lamps, said ballasting winding and said third winding being serially interconnected for connection with both of said lamps across said primary to form said series operating circuit for said lamps, said third winding being connected in voltage bucking relation to said ballasting winding in said operating circuit thereby to reduce the operating voltage applied to said lamps.

5. Ballast apparatus for sequentially igniting and operating a pair of fluorescent lamps in a series operating circuit from a relatively high voltage alternating current source, comprising a transformer having a magnetic core with an elongated winding leg and an outer yoke member, a high reactance starting secondary winding having

sufficient reactance so that said starting winding is substantially isolated from the operating circuit, a high reactance ballasting secondary winding, a primary winding and a third secondary winding all located on said winding leg, with said third secondary winding being closely coupled to said primary, a capacitive reactor connected in series circuit relation with said ballasting winding and said third secondary winding for interconnection with both of said lamps across said primary, said third winding being connected in voltage bucking relation to said ballasting winding in the series connection with said capacitive reactor, said starting winding, said primary winding, and said third winding forming a series operating loop for starting one of said lamps whereby said voltage across said third winding is in an aiding relation with the voltage across said primary winding and said starting winding being connected from one side of said primary winding to the juncture between said ballasting winding and said third winding whereby said voltage across said third secondary winding is in an opposing relation to the voltage across said ballasting secondary winding during operation of said lamps.

6. The apparatus of claim 5 wherein said third winding is wound over said primary winding, said ballasting winding and said starting winding are disposed on opposite sides of said primary winding and flux leakage paths are provided between said primary winding and said ballasting and starting windings.
